ROTARY STEEL PLATE PRINTING MACHINE

Frank C. Marquardt, Brooklyn, N. Y., assignor to
American Bank Note Company, New York,
N. Y., a corporation of New York

Application October 10, 1932. Serial No. 637,188

9 Claims. (Cl. 101—153)

The invention relates to a rotary steel plate printing machine, and more particularly to the mechanism by which power is transmitted from the plate cylinder gear to the impression cylinder or D-roll.

In rotary steel plate printing machines, it is necessary in order to secure proper register upon all sheets printed during a run of the machine, to so actuate the impression cylinder or D-roll that each rotation thereof will be initiated with the plate cylinder and the impression cylinder or D-roll in exactly the same relative position. In this manner, accumulated error during a day's run of the machine is prevented, since there is 15 an automatic readjustment of parts following the making of each impression.

It is also necessary, in a printing machine of this type, that the impression cylinder or D-roll be permitted limited movement independently of 20 the gearing normally operative to drive same, said cylinder being frictionally driven from the plate cylinder so as to have the same angular speed as the plate at all times during the making of an impression, notwithstanding variation in 25 the heights of different portions of the plate due to undulations in the surface thereof produced during the bending of the plate. In fact, the impression cylinder or D-roll, during the making of the impression, is constantly rotated as a result 30 of this frictional engagement, the speed of the cylinder, at times being momentarily higher than that of its gear, at other times being momentarily lower than that of its gear, while still at other times its speed will be that of its gear. Hence, 35 during the making of an impression, while power will be continuously applied to the impression cylinder or D-roll gear, such power will impart no rotative movement to the cylinder except through springs as hereinafter noted.

With the above conditions in mind, the machine of the invention is provided with an uninterrupted gear wheel carried by and rotatable with the plate cylinder gear, power being transmitted from said uninterrupted gear to the impression cylinder or D-roll through two gear segments, one of which is positively connected with the impression cylinder or D-roll, and the other of which, while positively driven by said uninterrupted gear, is idly mounted in relation to the 45 impression cylinder or D-roll, but is connected therewith through a spring rigging so constructed and arranged as to permit limited free movement of the impression cylinder or D-roll during its engagement with a plate upon the plate cylinder, while at the same time developing a ten-

sion in the springs forming a part of said rigging sufficiently great to secure a readjustment of the parts of the mechanism immediately following and during the making of each impression so as to ensure substantial exactitude in the position of 60 the impression cylinder or D-roll in relation to a plate upon the plate cylinder during the making of each impression and prior to the making of the succeeding impression.

The springs of the spring rigging above referred 65 to, during the making of an impression, will be under tension, which tension will be increased or lessened by variation in the speed of the impression cylinder or D-roll due to varying heights of different portions of a plate. If the speed of 70 the cylinder or D-roll be momentarily increased, the tension of the springs will be momentarily decreased, while if the conditions of the steel plate are such as to momentarily reduce the friction between the plate and the impression cylinder or D-roll, resulting in a lowering of the speed of the latter, the spring tension will be momentarily increased. The effect of this change of tension in the springs is to check any tendency of 75 the impression cylinder or D-roll to develop a 80 speed other than that determined by the condition of the printing plate and the frictional engagement between said plate and the blanket upon the impression cylinder or D-roll.

The impression cylinder or D-roll receives rotation during each cycle, which may be divided into four distinct stages: a positive movement during the enmeshment of the uninterrupted gear carried by the plate cylinder gear with the rack segment connected directly with the impression cylinder or D-roll; movement as a result of tensioning of the springs of the spring rigging immediately following the passing of the rack segment connected directly with the impression cylinder or D-roll from enmeshment with its actuating gear, 85 continuing until the blanket upon the impression cylinder or D-roll engages a plate upon the plate cylinder; movement as a result of the frictional engagement between said blanket and said plate, and finally, movement by spring tension following 90 the disengagement of the blanket from a plate until the re-enmeshment of the first mentioned rack segment with its gear.

During the three stages following the passing of the rack segment from its actuating gear, the 105 spring tension developed will be governed by the enmeshment of a segmental rack, idly mounted in relation to the impression cylinder or D-roll, with the same gear which co-operates with or actuates the segmental rack for imparting posi- 110

tive rotary movement for a short interval to said cylinder or D-roll. While, during the making of the impression, there may be rapid and frequent variations in the angular speed of the impression cylinder or D-roll, there will be continuous unidirectional rotary movement of said cylinder or D-roll at all times while the machine is in operation.

The construction and arrangement of the two 10 segmental gears or racks, one operative positively and directly upon the impression cylinder or D-roll and the other operative thereon through a spring rigging, is such as to limit the tension developed in the springs, which is particularly 15 desirable for ensuring a positive rotation of the impression cylinder or D-roll following its disengagement from a plate, the gear segment, directly and positively connected with the impression cylinder or D-roll, co-operating with the 20 other gear segment ensuring this action.

While, during the making of an impression, the impression cylinder or D-roll is rotated as a result of frictional engagement with the plate, it is nevertheless being acted upon at all times 25 by the tension of the springs of the spring rigging to ensure the desired variation in the cylinder speed with changes in the height of different portions of the plate.

The mechanism for rotating the impression 30 cylinder or D-roll is so constructed, in the machine of the invention, as to minimize wear upon the enmeshed gearing, to act with equal reliability irrespective of whether one or a plurality of plates are used upon the plate cylinder, and to 35 automatically restore the various parts of the power transmitting mechanism to their normal position, following the making of each impression, with a speed and reliability ensuring a smooth continued working of the machine.

40 The invention consists primarily in a rotary steel plate printing machine embodying therein a plate cylinder, an impression cylinder or D-roll, a continuous gear carried by, and rotatable with, said plate cylinder, two segmental gears adapted to mesh with said continuous gear, one 45 of which is connected directly with, and the other of which is idly mounted in relation to, said impression cylinder or D-roll, and a spring rigging connecting said idly mounted segmental gear with said impression cylinder or D-roll, whereby said impression cylinder or D-roll may 50 have varying angular movement relative to said continuous gear; and in such other novel features of construction and combination of parts 55 as are hereinafter set forth and described, and more particularly pointed out in the claims hereto appended.

Referring to the drawings,

Fig. 1 is a side view of the printing couple of 60 a rotary steel plate printing machine embodying the invention, with a portion of the plate cylinder gear broken away;

Fig. 2 is a side elevation from the left of Fig. 1, showing fragmentary portions of the plate cylinder and of the impression cylinder or D-roll;

Fig. 3 is a section on the line 3—3 of Fig. 2; and

Fig. 4 is a section on the line 4—4 of Fig. 1.

Like numerals refer to like parts throughout 70 the several views.

In the embodiment of the invention shown in the drawings, a fragmentary portion of the plate cylinder is shown at 10 and the main actuating gear therefor at 11, said gear 11 being connected 75 with the cylinder 10 in any desired manner to

ensure the continuous application of power to said cylinder. In the accompanying drawings the gear is shown as being keyed to the arbor 12 of the plate cylinder. So far as the present invention is concerned, however, the manner of transmitting power from the gear 11 to the cylinder 10 is immaterial.

A fragmentary portion of the impression cylinder or D-roll is shown at 13. This impression cylinder or D-roll is of the usual construction. When the plate cylinder 10 is constructed so as to receive two plates, it is customary to have the impression cylinder or D-roll one-half the diameter of the plate cylinder, said impression cylinder or D-roll receiving one rotation for each plate upon the plate cylinder. If three plates are used upon the plate cylinder, the diameter of the impression cylinder or D-roll will be one-third that of the plate cylinder, and said impression cylinder or D-roll will receive three rotations during each 95 full rotation of the plate cylinder.

In machines of the type to which the invention relates, when a plurality of plates are mounted upon said cylinder they are spaced in relation to each other to afford an interval during which 100 a proper feeding of the polishing and wiping webs may be effected. It is also customary to interrupt the surface of the impression cylinder or D-roll, to afford space for the mechanisms used in securing and tightening the blanket to and 105 upon said cylinder, the gap thus formed coinciding with the space between succeeding plates upon the plate cylinder during the operation of the machine.

The present invention relates more particularly 110 to the mechanism by which power is transmitted from the gear 11 to the impression cylinder or D-roll 13 in a manner to permit the frictional drive of the impression cylinder or D-roll 13 by plates upon the plate cylinder 10 during the making 115 of an impression, and the establishment of a definite relation of the impression cylinder or D-roll to the plate cylinder immediately following the making of one impression and prior to the making of the succeeding impression.

In the embodiment of the invention shown in the drawings, this power transmitting mechanism comprises a gear 14 carried by and rotatable with the gear 11. In practice, this gear 14 has teeth differing in form and number from those 125 upon the gear 11, and is formed of bronze or other hard anti-friction metal to minimize wear upon said gear. The gear 14 is adapted to mesh with two gear or rack segments 15 and 16, one of which, 15, is rigidly connected with the arbor 17 of the impression cylinder or D-roll 13 and is of a length approximating the length in arc of the gap formed in the impression cylinder or D-roll 13. The other segmental gear or rack 16 is idly mounted upon the impression cylinder or 135 D-roll arbor 17 and is of a length in arc approximating that of the impression cylinder or D-roll between the opposite edges of the gap therein. The two segmental gears or racks 15 and 16 have a combined circumference sufficiently less than 140 that of the impression cylinder or D-roll, to permit limited movement of the segmental gear or rack 16 in relation to the segmental gear or rack 15 as indicated at 18 in Fig. 1. This construction, as will more fully appear hereinafter, is for 145 the purpose of permitting that slight movement of the impression cylinder or D-roll, and the gear or rack segment 15 in relation to the gear or rack segment 16, necessary to permit variation in the angular speed of the impression cylinder or D-roll 150

in relation to the main gear 11 and the tensioning of the springs of a spring rigging by which the gear or rack segment 16 is connected with said impression cylinder or D-roll so as to impart movement thereto under certain conditions which will be explained hereinafter.

Carried by and rotatable with the arbor 17 of the impression cylinder or D-roll is a collar 19 having four spring seat studs 20, 21, 22 and 23 projected toward, but spaced slightly from the gear or rack segment 16. Said gear or rack segment 16 is also provided with four spring seat studs 24, 25, 26 and 27 projecting toward, but spaced from the collar 19. These studs are 15 spaced 90° apart upon the gear or rack segment 16 and upon the collar 19 respectively, those upon said collar being staggered in relation to those upon said gear or rack segment. Each pair of studs 20 and 24; 21 and 25; 22 and 26, and 23 20 and 27 has seated between them, a spring 28, 29, 30 or 31. One of the studs of each pair, such as 20, 21, 22 and 23 is provided with a spring seat fitting such as 32, adjustable in relation to its stud by means of a screw threaded member 33 25 adjustably mounted in said stud and having a spring seat screw threaded thereon.

While I prefer to use four springs as shown and described, it is obvious that the number of such springs may be varied without any substantial change in the mode of operation of the machine.

The springs 28 to 31 are normally under tension, the action of the springs being limited by the engagement of one end of the gear or rack segment 16 with the end of the gear or rack segment 15, these segments being aligned with each other.

In the accompanying drawings, the gear or rack segment 15 is carried by an arm 34 upon the plate 35 rigidly secured to the end of the arbor 17, the gear or rack segment 15 being offset with relation to the arm 34, as shown more particularly in Fig. 2, to bring it into alignment with the gear or rack segment 16.

While the gear 14 is a continuous gear, and during the normal operation of the machine has no movement as to any part thereof in relation to the main gear 11, I preferably so construct said gears 11 and 14 as to permit slight adjustment of the latter in relation to the former to permit adjustment of the impression cylinder or D-roll in relation to the plate cylinder under certain conditions well known to those familiar with the type of machine to which the invention relates. 55 The manner of mounting the gear 14 upon the gear 11 will now be described.

One side of the gear 11 is rabbeted to form a seat for the gear 14. Secured to the gear 14 by means of bolts 36 is a plate or plates 37. The plate or plates 37 has therein a slotted opening, as 38, through which bolts 39, connected with the rim of the gear 11, pass and project to an extent to receive lock nuts 40. Carried by the rim of the gear 11 is a fitting 41 having spaced arms 42 and 43 parallel with and adjacent a plate 36. A screw threaded stud 44, carried by one of the plates 36, is positioned between, but spaced from, the arms 42 and 43. Mounted in the screw threaded stud 44 is an adjusting screw 45, the ends of which respectively engage the arms 42 and 43.

The operation of the herein described mechanisms is substantially as follows:

The position of parts, as shown in Fig. 1, is that prevailing immediately following the mak-

ing of an impression, the gear or rack segments 15 and 16 both being enmeshed with the gear 14, one end of the gear or rack segment 16 being engaged with an end of the gear or rack segment 15, as shown, at the right of said segment or rack 80 15, and the opposite ends of said segments being spaced apart to form the gap 18 at the left of said segment or rack 15.

With the parts in this position, the recessed portion of the impression cylinder or D-roll is presented downwardly, and with the rotation of the plate cylinder 10 and the gears 11 and 14, rotary movement is imparted to the impression cylinder or D-roll solely through the gear or rack segment 15. Such movement of the impression 190 cylinder or D-roll is a positive drive from the plate cylinder gear and will continue so long as the gear or rack segment 15 is enmeshed with the gear 14.

With the parts in this position, the various 95 springs 28 to 31 are at their normal tension. As the gear or rack segment 15 passes from enmeshment with the gear 14, the end of the segment 16, to the left, Fig. 1, meshes with the gear 14, and aside from a continued rotation of the impression cylinder or D-roll 13, as a result of the 100 momentum of its mass, substantially no power will be operative upon the impression cylinder or D-roll, since as the normal tension of the springs 28 to 31 is insufficient to pick up the load of said cylinder the gear or rack segment 16 receives a 105 short rotary movement upon the arbor 17 until the tension of the springs 28 to 31 has been increased to an extent to assume the load of the impression cylinder or D-roll in a manner to continue its rotary movement until overtensioning of said springs may cause engagement of one end 110 of the gear or rack segment 16 with an end of the gear or rack segment 15 causing a positive cylinder movement for a sufficient interval to 115 allow such expansion or reaction of the springs 28 to 31 as will result in an approximate centering of the segment 15 in the space between the ends of the segment 16.

Plates of different lengths may be mounted, 120 at different times, upon the plate cylinder, but there will always be an interval of engagement of the gear 14 and the segment 16 prior to the engagement of the forward edge of any plate with the blanket upon the impression cylinder or D-roll 13, and this interval may vary with different sized plates unless other adjustments are provided in the machine to ensure accuracy in the timing of the engagement of the forward edge of each plate with the blanket upon the impression cylinder or D-roll irrespective of the size of the plate. The present invention, however, is not limited to use with a machine having such 125 adjustments.

Immediately upon the engagement of the forward edge of a plate with the blanket upon the impression cylinder or D-roll, the friction developed by such engagement will during the making of the impression control the rotary movement of the impression cylinder or D-roll. If the conditions in any part of a plate shall be such as to momentarily increase the speed of the impression cylinder or D-roll, as compared with the angular speed of the gear 14, the springs 28 to 31, not only permit such variation of speed, but will assist in ensuring the initiation and termination of same.

If a low spot occurs in the plate or, if after acceleration of the impression cylinder or D-roll, the condition of the plate will be such as to re-

sult in a reduction of the speed of the impression cylinder or D-roll, the springs 28 to 31 will be slightly compressed, thus not only permitting this reduction of speed, but resisting any tendency toward momentum of the cylinder causing it to exceed, even slightly, the speed required by the conditions of a plate.

- 10 The segment 16 during its enmeshment with the gear 14 has a substantially uniform speed so that retardation of the movement of the impression cylinder or D-roll in relation to that of the gear 14 will cause an increase in the tension of the springs 28 to 31 with a sort of braking action on the cylinder movement.
- 15 The construction herein shown and described will also compensate for any irregularities in the action of the gear 14 upon the segments 15 and 16 due to any possible slight irregularities in the teeth of these gears and segments arising during 20 their construction or resulting from wear thereon.

When the gear 14 is enmeshed with the segment 16, the springs 28 to 31 are subjected to continuing tensioning stresses, so that at all times during the making of an impression, some power 25 represented by the tension of these springs, is applied to the impression cylinder or D-roll. At times, when the impression cylinder or D-roll is not engaged with the plate, or when the angular speed of the cylinder is reduced as compared with 30 the angular speed of the gear 14, which latter condition results in an absence of, or lowering of the friction developed between the plate and the blanket of the impression cylinder or D-roll, the power applied to the cylinder through the springs, 35 will be the result of the direct action of the gear 14 upon the segment 16. When, however, the angular speed of the impression cylinder or D-roll is increased in relation to that of the gear 14, the power applied to the impression cylinder or 40 D-roll will be limited to the expansive force of these springs.

The power applied to the impression cylinder or D-roll during the making of the impression is derived from two sources, that resulting from the 45 frictional engagement between the blanket of the impression cylinder or D-roll and the plates upon the positively driven plate cylinder, and that resulting from the tensioning of the springs 28 to 31 through the plate cylinder gear 14 and the 50 segment 16. With an increase of the frictional power due to a high area in the plate, there will be a lowering of the spring power because of the free expansion of the springs due to the acceleration of the impression cylinder or D-roll. Inversely with the lowering of the frictional power 55 due to a low area, there will be an increase of the tension of the springs. Consequently, there will be during the making of an impression a continuing equalization of the sum of the power derived from the two sources upon the impression cylinder or D-roll, so that at all times during the making of an impression, it will have applied thereto a substantially uniform force avoiding 60 any fluctuation in its speed from any source other than the variation in the height of the surface of the plate, excepting those which may result from variation in the speed of the plate cylinder itself.

70 The speed variations of the impression cylinder or D-roll may be extremely rapid and may cover only an interval of a small fraction of a second and the spring power herein described has been found, in actual practice, to ensure fluctuation or variation in the speed of the impres-

sion cylinder or D-roll with a rapidity commensurate with the short time intervals involved.

The particular construction of parts is such as to permit the development of sufficient spring power to assume the load of the impression cylinder or D-roll when it is not engaged with the plate. At the same time, its construction is such as to avoid any possible interference with its free operation under all conditions.

80 The adjusting means for the gear 14 is used primarily for securing minute adjustment of the impression cylinder or D-roll in relation to the plate cylinder during the assembling of the machine or to compensate for slight wear upon the gears.

85 Steel plate printing machines are used for producing a class of work which requires absolutely perfect impressions in the finished product, and such impressions can result only when the angular speed of the plate cylinder and of the impression cylinder or D-roll are identical. Slight movement of the impression cylinder or D-roll in relation to a plate may result in ragged or broken lines or even smutting of the impression, 90 which is prohibitive. The cylinders of the printing couple are large heavy cylinders, and prior to my present invention, so far as I am aware, no means have been devised by which any equalizing action of the two sources of power during the making of an impression has been accomplished.

95 It is not my intention to limit the invention to the precise details of construction shown in the accompanying drawings, it being apparent that such may be varied without departing from the 100 spirit and scope of the invention.

Having described the invention, what I claim as new and desire protected by Letters Patent, is:—

1. A rotary steel plate printing machine embodying therein a plate cylinder, an impression cylinder or D-roll, a continuous gear carried by, and rotatable with, said plate cylinder, two segmental gears adapted to mesh with said continuous gear, one of which is connected directly with, 115 and the other of which is idly mounted in relation to, said impression cylinder or D-roll, and a spring rigging connecting said idly mounted segmental gear with said impression cylinder or D-roll, whereby said impression cylinder or D-roll 120 may have varying angular movement relative to said continuous gear.

2. A rotary steel plate printing machine embodying therein a plate cylinder, an impression cylinder or D-roll, a continuous gear carried by, 130 and rotatable with, said plate cylinder, two segmental gears adapted to mesh with said continuous gear, one of which is connected directly with, and the other of which is idly mounted in relation to, said impression cylinder or D-roll, a collar 135 carried by and rotatable with said impression cylinder or D-roll, a plurality of pairs of spring seat studs, one of each pair being carried by said idly mounted segmental gear and the other by said collar, and a spring mounted between the spring 140 seats of each pair, whereby said impression cylinder or D-roll may have varying angular movement relative to said continuous gear.

3. A rotary steel plate printing machine embodying therein a plate cylinder, an impression cylinder or D-roll, a continuous gear carried by, and rotatable with, said plate cylinder, two segmental gears adapted to mesh with said continuous gear, one of which is connected directly with, 145 and the other of which is idly mounted in rela- 150

tion to, said impression cylinder or D-roll, a collar carried by and rotatable with said impression cylinder or D-roll, a plurality of pairs of spring seat studs, one of each pair being carried by said idly mounted segmental gear and the other by said collar, and a spring mounted between the spring seats of each pair, each of said springs being normally under tension, whereby said impression cylinder or D-roll may have varying angular movement relative to said continuous gear.

4. A rotary steel plate printing machine embodying therein a plate cylinder, an impression cylinder or D-roll, a continuous gear carried by, and rotatable with, said plate cylinder, a long segmental gear idly mounted in relation to said impression cylinder or D-roll, a relatively shorter segmental gear connected directly with said impression cylinder or D-roll and having its teeth in alinement with the teeth of said idly mounted segmental gear, the relative dimensions of said segmental gears being such as to permit limited movement of said idly mounted segmental gear in relation to said other segmental gear, and a spring rigging connecting said idly mounted segmental gear with said impression cylinder or D-roll, whereby power from said plate cylinder gear, while enmeshed with said idly mounted segmental gear, will develop a tension in said springs, said impression cylinder or D-roll may have varying angular movement relative to said plate cylinder gear, and the tension of said springs will vary with varying angular speed of said impression cylinder or D-roll.

5. A rotary steel plate printing machine embodying therein a plate cylinder, an impression cylinder or D-roll, a continuous gear carried by, and rotatable with, said plate cylinder, a long segmental gear idly mounted in relation to said impression cylinder or D-roll, a relatively shorter segmental gear connected directly with said impression cylinder or D-roll and having its teeth in alinement with the teeth of said idly mounted segmental gear, the relative dimensions of said segmental gears being such as to permit limited movement of said idly mounted segmental gear in relation to said other segmental gear, a collar carried by and rotatable with said impression cylinder or D-roll, a plurality of pairs of spring seat studs, one of each pair being carried by said idly mounted segmental gear, and the other by said collar, and a spring mounted between the spring seats of each pair, whereby power from said plate cylinder gear, while enmeshed with said idly mounted segmental gear, will develop a tension in said springs, said impression cylinder or D-roll may have varying angular movement relative to said plate cylinder gear, and the tension of said springs will vary with varying angular speed of said impression cylinder or D-roll.

6. A rotary steel plate printing machine embodying therein a plate cylinder, an impression cylinder or D-roll, a continuous gear carried by, and rotatable with, said plate cylinder, a long segmental gear idly mounted in relation to said impression cylinder or D-roll, a relatively shorter segmental gear connected directly with said impression cylinder or D-roll and having its teeth in alinement with the teeth of said idly mounted segmental gear, the relative dimensions of said segmental gears being such as to permit limited movement of said idly mounted segmental gear in relation to said other segmental gear, a collar carried by and rotatable with said impression cylinder or D-roll, a plurality of pairs of spring seat studs, one of each pair being carried by said idly mounted segmental gear, and the other by said collar, and a spring mounted between the spring seats of each pair, each of said springs being normally under tension, whereby power from said plate cylinder gear, while enmeshed with said idly mounted segmental gear, will subject said springs to continuing tensioning stresses, said impression cylinder or D-roll may have varying angular movement relative to said plate cylinder gear, and the tension of said springs will vary with varying angular speed of said impression cylinder or D-roll.

7. A rotary steel plate printing machine embodying therein a plate cylinder, an impression cylinder or D-roll, a continuous gear carried by, and rotatable with, said plate cylinder, two segmental gears adapted to mesh with said continuous gear, one of which is connected directly with, and the other of which is idly mounted in relation to, said impression cylinder or D-roll, a spring rigging connecting said idly mounted segmental gear with said impression cylinder or D-roll, whereby said impression cylinder or D-roll may have varying angular movement relative to said continuous gear, and means whereby said continuous gear may be adjusted circumferentially of said plate cylinder to vary the relation of said impression cylinder or D-roll in relation to said plate cylinder.

8. A rotary steel plate printing machine embodying therein a plate cylinder, an impression cylinder or D-roll, a continuous gear carried by, and rotatable with, said plate cylinder, a long segmental gear idly mounted in relation to said impression cylinder or D-roll, a relatively shorter segmental gear connected directly with said impression cylinder or D-roll and having its teeth in alinement with the teeth of said idly mounted segmental gear, the relative dimensions of said segmental gears being such as to permit limited movement of said idly mounted segmental gear in relation to said other segmental gear, a spring rigging connecting said idly mounted segmental gear with said impression cylinder or D-roll, whereby power from said plate cylinder gear, while enmeshed with said idly mounted segmental gear, will develop a tension in said springs, said impression cylinder or D-roll may have varying angular movement relative to said plate cylinder gear, and the tension of said springs will vary with varying angular speed of said impression cylinder or D-roll, and means whereby said continuous gear may be adjusted circumferentially of said plate cylinder to vary the relation of said impression cylinder or D-roll in relation to said plate cylinder.

9. A rotary steel plate printing machine embodying therein a plate cylinder, an impression cylinder or D-roll, a continuous gear carried by, and rotatable with, said plate cylinder, a long segmental gear idly mounted in relation to said impression cylinder or D-roll, a relatively shorter segmental gear connected directly with said impression cylinder or D-roll and having its teeth in alinement with the teeth of said idly mounted segmental gear, the relative dimensions of said segmental gears being such as to permit limited movement of said idly mounted segmental gear in relation to said other segmental gear, a collar carried by and rotatable with said impression cylinder or D-roll, a plurality of pairs of spring seat studs, one of each pair being carried by said idly mounted segmental gear, and the other by said collar, a spring mounted between the spring seats of each pair, each of said springs being normally under tension, whereby power from said plate cylinder gear, while enmeshed with said idly mounted segmental gear, will subject said springs to continuing tensioning stresses, said impression cylinder or D-roll may have varying angular movement relative to said plate cylinder gear, and the tension of said springs will vary with varying angular speed of said impression cylinder or D-roll.

under tension, whereby power from said plate cylinder gear, while enmeshed with said idly mounted segmental gear, will subject said springs to continuing tensioning stresses, said impression cylinder or D-roll may have varying angular movement relative to said plate cylinder gear, and the tension of said springs will vary with vary-

ing angular speed of said impression cylinder or D-roll, and means whereby said continuous gear may be adjusted circumferentially of said plate cylinder to vary the relation of said impression cylinder or D-roll in relation to said plate cylinder.
